SIFTER TOP

Alex Limbach, Carmel, N. Y.

Application February 8, 1935, Serial No. 5,629

9 Claims. (Cl. 221—62)

This invention relates to sifter tops and the manufacture thereof. This invention relates particularly to sifter tops adapted to be used in connection with containers for finely divided materials such as powdered cosmetics and the like.

It is a purpose of this invention to afford sifter tops which can be made and assembled inexpensively and to afford sifter tops which have increased convenience and adaptability in use.

Heretofore sifter tops for containers for cosmetics and the like have been made with various forms of relatively sliding members and the like which as compared with the device of this invention are costly to manufacture. Likewise the assembly of such prior sifter tops with containers has been expensive as a special tool of some sort for uniting the two parts together has been required.

It is a feature of this invention that the sifter tops can be inexpensively made in two pieces from sheet metal. It is a further feature that the sifter top can be assembled without a special machine or crimping. Likewise one of the parts of the sifter top can be at the same time the breast and neck of the container so that the entire neck, breast and top closure can be made in only two pieces. Further features of this invention are that the closure is self opening and closing (by gravity); that is, the closure automatically opens upon inverting the container and closes tightly enough upon turning the container right side up to keep the scent in the cosmetic, for example, from escaping and to keep dust and dirt out of the container. A further feature of a preferred embodiment of this invention is that the closure can be positively closed as for shipment and sale as well as for use in traveling. The top can be opened readily by pulling it out either straight or with a twisting motion.

Further purposes, features and advantages of this invention will be apparent in connection with the following description of an illustrative embodiment of this invention shown in the accompanying drawing wherein,

Fig. 1 is a perspective view of a container having a sifter top embodying this invention.

Fig. 2 is a side sectional view of the sifter top with the container to which it is attached partially inverted.

Fig. 3 is a similar view to that shown in Fig. 2 with the container to which the sifter top is attached right side up.

Fig. 4 is a side sectional view of the sifter top with the closure pushed downwardly into positively closed position with respect to the neck.

In the drawing a container 10 is shown which can be of any desired size or shape. Secured to the container 10 as by friction is the member indicated generally by the reference character 11, which member comprises the breast portion 12 and the neck 13. The member 11 is preferably made from a single piece of metal as by stamping.

Within the neck 13 is the closure which is indicated generally by the reference character 14. The closure comprises a throat 15 loosely fitting within neck 13. The throat 15 fits loosely within the neck 13 in such manner that there will be sufficient clearance between the outside diameter of the throat and the internal diameter of the neck to permit finely divided material in the container to sift therethrough. The amount of clearance can be made as desired depending upon the fineness of subdivision of the material in the container, and the rate of flow desired. Preferably both the neck 13 and throat 15 are of substantial length so that the position of the closure 14 is guided by neck 13.

Spaced from the ears 16 is the closure shoulder 17 which is adapted to rest, for example, against the top of the neck 13 and preferably seats snugly against neck 13. Above the shoulder 17 is the friction locking surface 18 and at the top of the closure is a stop shoulder 19 which preferably has knurlings 20 therearound. The stop shoulder 19 preferably projects only slightly from surface 18 so as not to catch powder that is sifted through the sifter top. The end of the closure is imperforate as shown so as to prevent the escape of material in the container except through the space between the throat 15 and neck 13.

When the container 10 is in an upright position the parts of the sifter top are in the position shown in Fig. 3. The weight of the top 14 is sufficient to cause it to fall by gravity so that the shoulder 17 rests against the top of neck 13. The closure thus made is sufficient in normal use when the container is left on a bureau top, for example, as the closure is sufficiently tight to keep the scent of material in the container from escaping and to prevent dust and dirt from getting within the container. When it is desired to sift material in the container through the sifter top the container is inverted in the usual way and this causes the parts to assume the position shown in Fig. 2. There is sufficient spacing between the shoulder 17 and the ears 16 to permit longitudinal movement of the throat 15 in neck 13 so that a substantial space is afforded between the shoulder 17 and the top of neck 13. Since there is substantial clearance between throat 15 and neck 13 and since

the shoulder 17 is spaced from the top of neck 13, the contents of the container may be readily sifted out to the extent desired. When the desired amount of the material has been removed, the 5 container is merely turned upright and the parts assume the position shown in Fig. 3 thus effectively closing the container again.

If it is desired to more permanently close the sifter closure this can be readily done merely by 10 pressing the closure 14 downwardly until the parts assume the position shown in Fig. 4. The frictional locking surface 18 preferably is slightly inclined so as to be smaller in diameter at the bottom than at the top. The difference in diameter 15 between the bottom and top may be about five thousandths of an inch, for example. The external diameter of surface 18 is preferably approximately the same as the internal diameter of the neck 13 so that the shoulder 17 will normally rest upon the top of neck 13 but can, by 20 moderate pressure, be pushed down into the neck so that the inside of neck 13 will be in frictional contact with surface 18. The slight taper or inclination of surface 18 is such that the further 25 the top 14 is pushed into neck 13 the tighter it will be held. The limit to which the closure can be pushed in is determined by the stop 19.

When the parts are in the position shown in Fig. 4 the top 14 is held in neck 13 against accidental displacement. This is desirable in original 30 shipment and also is advantageous when, for any reason such as the packing of such containers in articles of luggage, it is desired to securely close the container. The sifter top can be readily 35 opened either by pulling it straight out or with a twisting motion. Usually a combined twisting and pulling motion is very convenient and it is to be noted that the opening of the sifter top lends itself to such movement. 40 Frictional closing is normally sufficient to positively close the sifter top, but the frictional closing means may be used in connection with or substituted by other positive closing means operable by manipulation of the top 14 relatively 45 to the neck 13. Thus any means for positively preventing the separation of the shoulder 17 from the neck 13 and securing the closure with reference to the neck so that material in the container cannot escape, may be used. However, the frictional means above described is regarded as 50 preferable.

As has been pointed out above other features of my invention relate to economy in manufacture and assembly. It has been pointed out above 55 that the top member 11 comprising breast 12 and neck 13 can be readily stamped from one piece of metal. Likewise the closure 14 can be made from a single piece of metal. Thus in making closure 14 a metal disc can be shaped into a cylinder 60 closed at one end and the cylinder can then be given the contour above described. The metal used is preferably a resilient metal so that ears 16 will have a certain amount of resiliency. The parts 11 and 14 can be made from the same type 65 of metal very inexpensively. While one piece construction of the parts 11 and 14 is regarded as preferable, these parts respectively can be made from a plurality of pieces of metal while still taking advantage of some of the features of this 70 invention.

To assemble the parts all that is necessary is to push the closure 14 down into the neck 13. Since the ears 16 are resilient they will be retracted out of the way and upon full insertion of 75 the throat 15 into neck 13 the ears 16 will spring

out again to afford stop means adapted to prevent the withdrawal of the closure 14 from the neck 13. It is to be noted that the operation is most simple and can be performed by unskilled labor without any tool. This is of great advantage and is to be contrasted with methods of assembly heretofore used wherein a sifter top device has been inserted in the top of a container and has been secured thereto as by crimping in an operation requiring special machinery and skilled 10 labor.

While this invention has been described in connection with certain specific embodiments thereof it is to be understood that this has been done merely for purposes of illustration. Referring to the closure 14 it is apparent that it may take different forms and likewise it may be used with containers having an opening either with or without a neck adapted to receive the same and such opening can either be or not be associated with a breast portion of a container. It is believed however that the foregoing is sufficient to enable one to understand and practice this invention which is to be governed as to scope by the language of the following claims.

I claim:

1. A sifter top comprising a member having a neck, and a closure for said neck comprising a throat portion loosely fitting within said neck, there being a space between the exterior of said throat portion and the interior of said neck adapted for the passage of finely-divided material therethrough, an imperforate outer end, a portion intermediate said end and said throat adapted for frictional contact with said neck and 30 to substantially prevent the escape of finely-divided material between said portion and said neck when said portion is in frictional contact with said neck, and stop means for preventing the withdrawal of said throat from said neck but 35 permitting limited free longitudinal movement of said throat in said neck.

2. A sifter top which comprises a member having breast and neck portions and a closure for said neck portion, said closure comprising a 45 throat portion slideable by gravity within said neck, there being a space between the exterior of said throat portion and the interior of said neck adapted for the passage of finely-divided material therethrough, a shoulder having a maximum external diameter approximately the same as the 50 internal diameter of said neck, an imperforate outer end, an imperforate friction surface intermediate said end and said shoulder adapted to be pushed into and withdrawn from said neck 55 and conforming to said neck, and stops adjacent the ends of said closure adapted to prevent the ends of said closure passing through said neck, the throat portion of said closure having a limited longitudinal play between said shoulder and the 60 remote stop which is adjacent the end of said neck remote from said shoulder.

3. A sifter top which comprises a member having breast and neck portions and a closure for said neck portion, said closure comprising a 65 throat loosely fitting within said neck and of approximately uniform diameter, there being a space between the exterior of said throat portion and the interior of said neck adapted for the passage of finely-divided material therethrough, a shoulder at an end of said throat portion having a maximum diameter about the same as the internal diameter of said neck and adapted to rest against said neck, an imperforate end portion beyond said shoulder, releasable means 70

adapted to positively maintain said neck closed by said closure when said shoulder is pushed into said neck, and stop means adjacent the end of said throat remote from said shoulder adapted 5 to prevent withdrawal of said throat from said neck while permitting limited free movement of said throat in said neck so that the said shoulder can move from said neck when said sifter top is inverted for sifting finely divided material between said throat and said neck.

10 4. A sifter top including a one piece closure adapted to be inserted into an opening in a container, said closure comprising a first portion of substantial length loosely fitting within said opening, there being a space between the exterior of said first portion and the interior of said opening adapted for the passage of finely-divided material therethrough, a second portion of substantial length more adjacent the outer 15 end than said first portion which is adapted to fit frictionally within said opening and which is adapted to prevent the passage of finely-divided material between same and said opening when inserted in said opening, and a shoulder between 20 said first and second portions adapted to prevent said second portion being inserted in said opening except by substantial positive actuation.

25 5. A sifter top including a closure adapted to be inserted in an opening in a container, said closure comprising an imperforate outer end, a surface portion adapted to fit snugly within said opening of said container, a stop between said imperforate end and said surface portion, a throat portion loosely fitting within said opening and movable longitudinally by gravity therein, there being an annular space between the exterior of said throat and the interior of said opening adapted for the passage of finely-divided material therethrough, a shoulder between said 30 surface and throat portions, and a stop adjacent the other end of said closure adapted to prevent the withdrawal of said throat portion from said opening.

35 6. A sifter top including a closure adapted to be inserted in an opening in a container, said closure comprising an imperforate outer end, an imperforate surface portion adapted to fit snugly within said opening of said container, a stop between said imperforate end and said surface portion, an imperforate throat portion loosely fitting within said opening and movable longitudinally by gravity therein, there being an annular space between the exterior of said throat and the interior of said opening adapted for the passage 40 of finely-divided material therethrough, and a stop adjacent the other end of said closure adapted to prevent the withdrawal of said throat portion from said opening.

45 7. A sifter top which comprises a member having a breast and neck portion, and a closure for said neck, said closure comprising a throat portion loosely fitting within said neck and longitudinally slidably by gravity therein, there be-

ing a space between the exterior of said throat portion and the interior of said neck adapted for the passage of finely-divided material therethrough, a shoulder adapted to rest against said neck when said top is in upright position, means 5 for preventing said closure from falling out of said neck when said sifter top is inverted, and releasable means for positively preventing withdrawal of said shoulder beyond position for maintaining closed contact between said shoulder and said neck.

10 8. A sifter top which comprises a member having breast and neck portions and a one piece closure adapted to close said neck, said closure comprising an imperforate throat loosely fitting 15 within said neck, there being an annular space between the exterior of said throat and the interior of said neck adapted for the passage of finely-divided material therethrough, a shoulder having a larger diameter than said throat and 20 having a maximum diameter approximately the same as the inner diameter of said neck, which shoulder is adapted to seat against said neck adjacent the outer end thereof, an imperforate surface portion between said shoulder and the end 25 of said closure which is gradually tapered so as to be larger in diameter at the outer end than at the inner end and which is adapted to be pushed frictionally into said neck, the said end of said closure being imperforate, means adjacent one 30 end of said closure for preventing the withdrawal of said throat from said neck and means adjacent the other end of said closure for preventing said closure from being pushed through said neck into said container, which latter means is adapted 35 to be grasped in withdrawing said surface portion from frictional engagement with said neck.

9. A sifter top including a one piece closure adapted to be inserted into an opening in a container, said closure comprising an imperforate 40 throat of substantial length loosely fitting within said opening, there being an annular space between the exterior of said throat and the interior of said opening adapted for the passage of finely-divided material therethrough, an imperforate portion adapted to seat against said opening to close said opening and stop means adapted to prevent withdrawal of said throat from said opening, said throat having limited longitudinal movement within said opening so 45 that said portion can be moved by gravity into and away from seating position against said opening and said stop means including a resiliently retractable part adapted to permit said closure to be assembled in said opening merely by pushing said throat into said opening, and means intermediate said portion and the end of said closure adapted to positively close said opening by pushing said closure downwardly into said opening, said means and said end of said closure 50 being imperforate.

ALEX LIMBACH.
